[57] CLAIM

The ornamental design for a shoe mounted foot warmer pouch, as shown and described.

DESCRIPTION

FIG. 1 is a perspective view of a shoe mounted foot warmer pouch showing my new design;

FIG. 2 is a bottom perspective view thereof;

FIG. 3 is a top plan view thereof;

FIG. 4 is a bottom view thereof;

FIG. 5 is a side elevational thereof, the side not shown being a mirror of the side shown;

FIG. 6 is a front elevational view thereof;

FIG. 7 is a rear elevational view thereof; and,

FIG. 8 is a perspective view drawn to a smaller scale showing the shoe mounted foot warmer pouch mounted on a shoe which is represented by broken lines to illustrate environmental structure.

FIG. 1
